PLATE AND PANEL WITH INSCRIPTIONS OR DESIGNS

Application filed February 5, 1931, Serial No. 513,761, and in France December 11, 1930.

This invention relates to the manufacture of plates and panels with inscriptions or designs, capable of being used for road and urban signalling, advertising, motor car number plates, plates for the name and numbers of streets, placards for shop windows, and the like.

According to this invention, each plate or panel comprises, on the one hand, an inscription constituted by one or more members cut out according to the required designs in a thin sheet of metal, preferably brilliant and essentially presenting a surface with numerous parts in relief suitable to reflect light in all directions; these parts in relief can have the shape of juxtaposed pyramids or cones, of ribs arranged parallel or crosswise, or in herringbone, quincunx fashion, etc.; and, on the other hand, a covering sheet made of transparent and supple material, the outer face of which is plain and the inner face exactly fits the uneven or embossed surface of the metal sheet and intimately adheres thereto.

Generally speaking, the embossed or waved conformation of the metal sheet will be imparted thereto by compression against a suitable die, and one of the features of this invention consists in utilizing as a die a simple wire gauze composed of wires having a suitable size and suitably spaced apart; by firmly pressing this wire gauze against the elements cut out in a plain metal sheet, and themselves applied against a transparent covering sheet made of plastic material resting on a smooth surface, it is possible to easily obtain both the required conformation of these elements, that of the inner face of this transparent sheet and, besides, the adhesion of the latter to the elements thus stamped out.

The plasticity of the covering sheet will, preferably, be brought to the suitable degree by the action of heat and, if need be, a solvent or an adhesive can be used for increasing the adhesion of the metallic elements, so that, when taken out from the press, the whole structure will constitute a compact plate ready to be employed.

Instead of a wire gauze, use can be made

of a perforated sheet metal plate or of any other part capable of acting as a die, for instance a piece of net or tulle, etc., a cut out or engraved plate, etc., for obtaining the required goffering.

Another feature of the invention consists in uniting to the transparent covering sheet and to the waved metallic elements forming the inscription, a sheet the colour and opacity of which can be so chosen as to constitute a background or backing on which the inscription will be clearly displayed.

In this case, this backing sheet, when it is also constituted by a plastic material, can be placed against the inscription elements and the covering sheet before exerting pressure. The die being placed behind the backing sheet, will enter the same, and its projections or its solid portions will drive back both the superposed layers of plastic material and of thin metal by imparting to the same the required conformation and adherence.

If the die enters but slightly the plastic material, it will be possible to easily separate therefrom all the said superposed layers, which will then constitute a plate or a panel according to the invention.

But another important feature of this invention consists, on the contrary, in leaving the die, wire gauze or the like, incorporated in the plastic material, so that it becomes an integrant part of the plate or panel and constitutes for the latter a strengthening same.

It is thus possible to obtain by a single stroke of the press, the conformation, the final union and the reinforcement of all the parts, so as to rapidly and economically provide a panel which is unbreakable, undistortable, unalterable, which does not require any maintenance and perfectly lends itself to the various above mentioned uses owing to the very conspicuous effect due to the reflecting facets of the elements of the inscription or design.

The rear face of the panel can, if necessary, be covered with a sheet of cardboard, paper or the like adapted to protect it; this

sheet can be glued on to the backing plate under the action of the same stroke of the press which assembles all the parts.

When the die remains incorporated in the panel, it is possible, in certain cases, to use it as backing, so that the layer of plastic material provided for showing off the inscriptions or designs then becomes unnecessary.

A form of carrying out the subject-matter of the invention and modifications of embossed metallic elements are illustrated in the accompanying drawing by way of example.

Fig. 1 is an elevation, with parts broken away, of a panel bearing a very simple inscription.

Fig. 2 is a cross-section, on an enlarged scale, made according to line A—A of Fig. 1.

Figs. 3 and 4 illustrate portions of embossed metallic elements.

1 designates a covering sheet made of transparent plastic material, for instance a cellulosic material, 2 designates elements cut out according to the required design in a thin and brilliant metal sheet, for instance aluminum, 3 is a sheet of plastic material similar to the preceding one, but having a suitable coloration and opacity for constituting a background, 4 is a wire gauze having relatively large meshes, and 5 a cardboard sheet.

These various parts are assembled by pressure, with or without intervention of heat, solvents, or adhesives.

Usually, the compression will conveniently be exerted at a sufficient temperature in order that the sheets 1 and 3 may be sufficiently plastic and exactly fit the distortions of the metallic elements 2, in concordance with the solid portions and empty spaces of the wire gauze 4, so that, after crushing, no free space will be left between the various parts. In order to perfectly ensure the adherence of the latter, their contact faces can be covered with a suitable solvent before superposing them.

Fig. 1 shows that the surface of the elements 2 has taken, under the influence of pressure, an embossed shape, comparable to a network of interrupted ribs arranged in quincunx order, some according to one direction, the others at right angles thereto, thus forming a large number of facets reflecting light in all directions.

These ribs will be more or less accentuated according to the size of the meshes and wires, the plasticity of the material, the malleability of the brilliant metal and the degree of pressure.

If use is made, as a die, of a stamp or engraved plate, etc., it will be possible to produce in the sheets 1, 3 and elements 2 distortions of all kinds; Fig. 3 shows, for instance, projections in the shape of juxtaposed pyramids having a square base, and

Fig. 4 shows ribs arranged according to two oblique directions forming a very acute angle.

It is to be understood that instead of including the parts 1, 2, 3, 4, 5 indicated above, the panel can comprise only the parts 1, 2, 3, 4 or 1, 2, 3, 5, or even only the parts 1, 2, 3 or 1, 2, 4 or 1, 2, 5, if some of the advantages resulting from the complete combination are sacrificed.

By the term "plastic material" used in this specification is meant not only the cellulosic or like materials which are plastic at a low temperature, but also the materials which, as glass, become plastic at a high temperature and present, in the cold state, suitable qualities of transparency and strength.

On the other hand, the brilliant sheet in which are cut out the elements of the inscriptions or designs can be constituted, not only by a metal, but also by any other suitable brilliant or shining material, in sheet form.

Relating to the opaque backing sheet 5, it can be constituted by cardboard, or, generally speaking, by any material capable of receiving an impress, either in the natural condition or after a suitable preparation.

It is to be also understood that without departing from the scope of the invention, the designs, letters, digits, etc., of the inscriptions can be obtained in such a manner that they are set out by a dark or dull aspect on a brilliant background.

We claim:

1. In an advertising panel, the combination of a transparent plate, an opaque plate applied on one of the sides of the said transparent plate, and letters or designs made of thin and brilliant sheets clamped between both plates, the surfaces in contact of both plates being embossed so as to perfectly fit on each other and the letters and designs clamped between them having a corresponding embossed shape.

2. In an advertising panel, the combination of a transparent plate having a smooth side, an opaque plate on the side of the said transparent plate opposed to the smooth side of the latter, and letters or designs made of thin and brilliant sheets, clamped between both plates, the surfaces in contact of the said plates being embossed so as to perfectly fit on each other, and the letters and designs clamped between them having a corresponding embossed shape.

3. In an advertising panel, the combination of a transparent plate which may be rendered plastic at a low temperature and having a smooth side, an opaque plate also made of a material which can be rendered plastic at a low temperature and fitted on the side of the said transparent plate opposed to the smooth side of the latter, and letters or designs made of thin and brilliant

5 sheets clamped between both plates, the surfaces in contact of the said plates being embossed so as to perfectly fit on each other and the letters and designs clamped between them having a corresponding embossed shape.

10 4. In an advertising panel, the combination of a transparent plate having a smooth side, an opaque plate fitted on the side of the said transparent plate opposed to the smooth side of the latter, and letters or designs made of thin and brilliant metal and clamped between both plates, the surfaces in contact of the said plates being embossed so 15 as to perfectly fit on each other and the letters and designs clamped between them having a corresponding embossed shape.

20 5. In an advertising panel, the combination of a transparent plate made of a material which can be rendered plastic at a low temperature and having a smooth side, an opaque plate also made of a material which can be rendered plastic at a low temperature and fitted on the side of the transparent plate 25 opposed to the smooth side of the latter, letters or designs made of thin and brilliant sheets and clamped between both plates, and elements having an embossed surface, incorporated from the rear to the said opaque 30 plate, the surfaces in contact of the said plates and of the said letters or designs being embossed correspondingly to the said elements.

35 6. In an advertising panel, the combination of a transparent plate made of a material which can be rendered plastic at a low temperature and having a smooth side, an opaque plate also made of a material which can be rendered plastic at a low temperature 40 and fitted on the side of the said transparent plate opposed to the smooth side of the latter, letters or designs made of thin and brilliant sheets and clamped between both plates, and a grid incorporated from the 45 rear to the said opaque plate, the surfaces in contact of both plates and of the letters and designs clamped between them having an embossed shape corresponding to that of the said grid.

50 7. In an advertising panel, the combination of a transparent plate made of a material which can be rendered plastic at a low temperature and having a smooth side, an opaque plate also made of a material which can be rendered plastic at a low temperature 55 and fitted on the side of the said transparent plate opposed to the smooth side of the latter, letters or designs made of thin and brilliant sheets and clamped between both plates, and a wire gauze having large 60 meshes, incorporated from the rear to the said opaque plate, the surfaces in contact of both plates and of the letters and designs 65 clamped between them having an embossed

shape corresponding to the meshes of the said wire gauze.

In testimony whereof we have hereunto affixed our signatures.
